H. H. CHASE

WRENCH CONTAINER

Filed Oct. 5, 1923

FIG. 1

FIG. 2

FIG. 3

FIG. 4

Henry H. Chase

By *Clarence Walker*
His Attorney

UNITED STATES PATENT OFFICE.

HENRY H. CHASE, OF JAMESTOWN, NEW YORK.

WRENCH CONTAINER.

Application filed October 5, 1923. Serial No. 666,801.

To all whom it may concern:

Be it known that I, HENRY H. CHASE, a citizen of the United States, residing at 837 Fairmount Avenue, in the city of Jamestown, in the county of Chautauqua and State of New York, have invented certain new and useful Improvements in Wrench Containers, of which the following, taken in connection with the accompanying drawings, is a specification.

This invention relates to an improvement in a tool outfit and more particularly in a container for a socket wrench.

The chief object in this invention is to provide a container for a high speed wrench in which the brace, sockets and other parts are carried upon a suitably formed plate and detachably secured thereto by the manner of mounting one of the elements. Such a plate forms a convenient manner of storing and carrying the tools and by providing an easel support at the back the outfit can be displayed upon the store counter.

Other objects will appear from the examination of the following specification taken in connection with the drawing which forms a part thereof and in which—

Figure 1 is a front elevation of a container embodying one form of this invention;

Fig. 2 is an elevation of the plate alone, the parts being removed;

Fig. 3 is a transverse section taken along the lines 3—3 of Fig. 1; and

Fig. 4 is an end view taken from the left of Fig. 1.

This embodiment as shown is adapted to support a high speed socket wrench outfit which comprises a brace 10, sockets or couplers 11, and extensions 12, 13 and 14, varying in length. The outer contour of the extensions 12, 13 and 14 and the butt 15 of the brace 10 is here shown hexagonal. This formation is not necessary but is the one usually followed, the essential feature being that the outer contour of each of these parts should be the same. The sockets 11 are of the well-known No. 1 type both ends being provided with hexagonally formed recesses so as to receive the ends of the extensions, or the butt 15.

These elements are preferably mounted upon a plate 16 which is of the form shown in Fig. 2, notched flanges 17 being provided on the wider portion and higher flanges 18 having hexagonal openings 19 being provided

on the ends of the narrow portion. The notches 20 in the flanges 17 are preferably semi-circular, as shown particularly in Fig. 4. In the plate 16, preferably in line with flanges 18, are formed rectangular openings 21 which are made narrower than the sockets or couplers 11 but slightly longer so that when the latter are placed on the openings 21 they project therethrough, as shown in Fig. 3, and hence cannot shift their position when the parts are fully assembled as will be described later.

Thrown up from the plate 16 are straps 22 which, as shown particularly in Fig. 2, are arranged in pairs and straps 23 and 24 also arranged in pairs. A flange 25 on the lower edge of the plate 16 connects the flanges 17. The extensions 12, 13 and 14 are provided at each end with the usual spring pressed ball 26 which will be depressed when a socket or coupler is slipped over the ends of the extension.

Referring particularly to Figs. 1 and 3 it will be noted that the parts are assembled in the following manner. The sockets or couplers 11 are placed in the openings 21, the extension 12 is placed in the rectangle formed by the straps 23, 24 and the extension 13 is placed between the straps 22. The brace 10 placed in the notches 20 and rests against the plate 16 with one side lying between the flange 18 and the outer socket 11 and the other side lying between flange 18 and the extension 12. The flange 25 and the brace 10 limit the longitudinal movement of the extension 13. The extension 14 is now inserted through the openings 19 of the flanges 18, the spring pressed balls 26 preventing the involuntary removal of the extension 14 through the openings 19. It will be observed that the extension 14 prevents the removal of any of the other parts of the plate 16, as appears particularly in Fig. 3. When the parts are so installed the prop, or easel 27, hinged on the back of the plate 16, may be opened and the plate with its tools stood upon the counter or work bench, if desired.

While the sockets or couplers 11 have been described as identical in construction, it is obvious that other forms of sockets could be provided or that, if preferred, sockets of different sizes such as are shown in my earlier patent No. 1,438,900 could be used. By the use of the elements here described it would be possible to provide a high speed

wrench of any desired length. For example, brace 10 can be used alone with one of the sockets 11 or the socket 11 can be used as a coupler and provided with one of the extensions 12, 13 and 14 on the outer end of which can be installed another socket. This building-up process can be continued further until all the tools shown are employed to provide a high speed wrench of great length, and in such case an additional socket must be employed.

Although one embodiment only has been shown and described, I am not to be limited thereby since it is obvious that other embodiments may be made without departing from the spirit and scope of the invention as set forth in the following claims.

Having thus set forth my invention what I claim as new and for which I desire protection by Letters Patent is:

1. A container for a high speed wrench outfit including a brace, sockets and extensions consisting of a plate having holders for said elements comprising a plurality of

openings in which said sockets are placed, 25 notched flanges for receiving said brace, spaced straps for all but one of said extensions and flanges having openings therein in which one of said extensions is inserted, said last named extension extending over and locking said other elements in said holders. 30

2. A container for a high speed wrench outfit including a brace, sockets and extensions consisting of a plate having holders for said elements comprising a plurality of 35 openings in which said sockets are placed, notched flanges for receiving said brace, spaced straps for all but one of said extensions and flanges having openings therein in which one of said extensions is inserted, said last named extension having a spring 40 pressed ball in each end, which balls hold said extension in said flanges and said extension being so located as to lock said other elements in said holders. 45

In testimony whereof I have affixed my signature.

HENRY H. CHASE.
